Primary Examiner — Barbara Fox*Assistant Examiner* — Mary C Ramirez(74) *Attorney, Agent, or Firm* — Sughrue Mion, PLLC(57) **CLAIM**

The ornamental design for a lens for camera, as shown and described.

DESCRIPTION

FIG. 1 is a front, top, right perspective view of a lens for camera showing the new design;

FIG. 2 is a rear, top, left perspective view thereof;

FIG. 3 is a front view thereof;

FIG. 4 is a rear view thereof;

FIG. 5 is a plan view thereof;

FIG. 6 is a bottom view thereof;

FIG. 7 is a right side view thereof; and,

FIG. 8 is a left side view thereof.

The evenly spaced broken lines shown in the drawings depict portions of the lens for camera that form no part of the claimed design. The long-short broken lines depict the boundary of the claim and form no part of the claimed design.

1 Claim, 8 Drawing Sheets(56)
